UNITED STATES PATENT OFFICE

ERIK OTTO ERIKSSON, OF LIDINGO, SWEDEN, AND GUSTAV NORDGREN, OF LONDON, ENGLAND, ASSIGNEES TO AKTIEBOLAGET LJUNGSTRÖMS ANGTURBIN, OF STOCKHOLM, SWEDEN, A JOINT-STOCK COMPANY OF SWEDEN

BLADE RING FOR RADIAL FLOW ELASTIC FLUID TURBINES

Application filed October 13, 1928, Serial No. 312,233, and in Sweden October 15, 1927.

The present invention relates to blade rings for radial flow elastic fluid turbines and has particular reference to improvements in the construction of such rings for turbines of the so-called Ljungstrom type.

The blade rings of turbines of the above type consist of two or more annular axially spaced ring bonds with a plurality of blades secured between them, the several blade rings employed in a turbine being of different diameters and telescoped so as to provide a radial path of flow for the motive fluid through the blading.

In accordance with earlier forms of construction the turbine blades have been cut from lengths of profiled blank material and have had their ends fitted in holes of corresponding form provided in sheet metal rings, the blades being welded to the rings to provide a blade ring of generally cylindrical form. Projecting edges of dovetail section have then been formed on the sides of said ring, these edges then being fitted into corresponding annular slots or grooves in annular ring bonds with which they have been united to form a rigid unit by rolling or otherwise forcing the edges of the grooves in the ring bonds over the dovetail projections on the ring portions. The above described method of manufacture involves a number of serious disadvantages. In the first place the method is a poor one from an economical standpoint since it is necessary to provide various special auxiliary means to insure the proper positioning of the blades during the welding process. Furthermore the necessary heat treatment has an adverse affect on the durability of the material and also sets up stresses which tend to warp the blade rings and render difficult the production of blade rings which are of proper shape after being cooled subsequent to the welding operation.

It has been suggested, therefore, to make the blades out of a blank by milling the same, or by making the same in some other suitable manner so that two thicker end portions would be left on each plate, which portions would both be provided with dove-tail projections adapted to be fitted into correspondingly shaped annular grooves provided in the

ring bonds connected with said end portions and common to all blades, certain parts of the ring bonds being caused, by rolling or pressing operations, to overlap the projections of the dove-tail portions so that the blades would be retained in the ring bonds. This procedure is also very expensive, great accuracy being required in making the blades. All blades must be of absolutely the same length and must possess the exact peripheral width required by the pitch. Otherwise, the ring produced by the dove-tail portions of the blades will become uneven, or the blades will not entirely fill the annular slot or groove in which they are to be secured.

The general object of the present invention is to improve upon prior forms of blade ring construction and the manner in which this and the more detailed objects of the invention are attained may best be understood from the following description of the several examples of blade ring construction illustrated in the accompanying drawings forming a part of this specification.

Fig. 1 shows a cross-section of a radial flow elastic fluid turbine having blade rings rotating in opposite directions. Fig. 2 shows a section on an enlarged scale of a blade ring embodying the invention. Fig. 3 shows the same blade ring viewed from above. Fig. 4 shows a section of a blade ring on line 4-4 in Fig. 2. Fig. 5 shows a section of a blade ring on line 5-5 in Fig. 4. Figs. 6 and 7 illustrate other forms of ring bonds for carrying the invention into effect.

In Fig. 1, the center line 1 designates the axis of rotation of the turbine shaft 2, and the section line 3 indicates a plane with respect to which the blading of the turbine is axially symmetrical. The turbine illustrated comprises four blade systems 4, 5, 6 and 7. The motive fluid entering the turbine through the channel 8 flows through the above blade systems in the order named and gives up its energy to the blade rings, of which alternate blade rings rotate in opposite directions.

Figs. 2 and 3 illustrate a blade ring having a plurality of blades 10 each of which is shaped at its ends to provide heads 13 and 100

14, these heads being fitted respectively into grooves 13a and 14a in the respective ring bonds 15 and 16. These grooves open axially inwardly of the ring bonds and extend from the radially inner faces thereof in a generally radial direction partially through the material of the ring bonds, to form what may be termed blade retaining pockets.

In the example illustrated the part of the 19 turbine rotor to which the blade ring is attached is indicated at 21 and the ring is attached thereto by means of an articulated expansion ring 22 joining the parts 16 and 21.

In the present embodiment the end portions 15 of the blades are of dovetail form in peripheral section and the grooves 13a and 14a are of complementary dovetail form as will be seen from Fig. 5, and as will be evident from Fig. 3 which shows in dotted 20 lines the end portions of one of the blades 10, these end portions substantially fill the pockets provided by the grooves 13a and 14a. As will be seen from Fig. 4 the grooves 13a and 14a are circumferentially spaced so that 25 each blade is independently mounted between the ring bonds and any inaccuracy in the positioning of one blade will in no wise affect the accurate positioning of any other blade in the blade ring. The grooves 13a and 14a 30 are advantageously formed by means of an end mill and the end portions of the blades are inserted in the pockets from the radially inner sides of the ring bonds. It will be observed that the grooves in the ring bonds 35 which extend radially only partially through the material of the bonds, leave a full section of metal as at 12 (Fig. 2) at the outer peripheral portion of the ring bonds.

40 Due to the thickened end portions of the blades which in the present embodiment are of dovetail form, the blade ring is firmly held together as a unit against axial stresses tending to pull the blades from the ring bonds and when the turbine is in operation the centrifugal force acting on the blades holds them firmly in position in radial direction.

45 Due to the type of fastening each blade 50 may be considered independently as a beam fixed at both ends and with respect to the forces acting thereon due to rotation of the blade rings, the calculations for the blades may readily be made on the above basis.

55 In order to prevent any possibility of a 60 blade becoming dislodged from the ring bonds when not held in radial position by centrifugal force, it is preferable to provide means for locking the blade ends in their respective pockets. On the ring bond 15 in Fig. 2 one means of locking the blades is illustrated, this means comprising a groove 17 on the radially inner face of the ring bond adjacent to the bottoms of grooves 13a. This circumferential groove provides a flange 18

which may be readily beaded over the ends 13 of the blades after they are inserted.

The ring bond 16 illustrates another means for locking the blades in position. In this instance the end portion 14 of the blade has 70 less radial depth than the pocket 14a, thus permitting one or more of the edges of the blade retaining pocket to be beaded over the end portion of the blade as shown at 20.

The grooves 13a and 14a intended for each 75 blade may be milled out either radially or, as shown in Fig. 4, somewhat obliquely with respect to the radius. In the latter case, the dove-tail portions of the blades, and thus 80 also the grooves, extend preferably in or approximately in the direction of one moment axis of the blade. The dove-tail part will then be longer, which results in a stronger attachment. Also, less material is required in a 85 blade made in this manner.

Figs. 6 and 7 illustrate further forms of 90 pockets in the ring bonds by means of which the blades can be secured in accordance with the present invention. In the embodiment shown in Fig. 6 the pockets 13b are rectangular in section and open toward the axially inner face of the ring bond 15 through necks of less circumferential extent than the main body of the grooves.

In the embodiment illustrated in Fig. 7 the 95 grooves 13c are circular in section rather than rectangular as in the embodiment shown in Fig. 6 and likewise have relatively narrow necks providing openings between the main 100 portions of the grooves and the axially inner face of the ring bond.

From the foregoing descriptions it will be 105 evident that the invention is not dependent upon the specific shape of the end portions of the blades and the form of the pockets 110 in which they seat. Various shapes of blade ends other than those illustrated may be employed. The essential feature of the invention is the independent mounting of the blades in separate grooves so that the blades 115 may be separately manufactured and assembled and so that accurate positioning of any one blade in the blade ring will not be dependent upon the accuracy in manufacture or assembly of other blades therein.

Certain novel features of construction of the turbine rotor, herein disclosed but not claimed, form no part of the present invention and we are informed comprise the invention of Alf Lysholm claimed in his copending United States patent application, Serial No. 356,213.

120 What we claim as new and desire to secure by Letters Patent of the United States of America is:—

125 1. A blade ring for radial flow elastic fluid turbines comprising two axially spaced ring bonds having a plurality of separate circumferentially spaced grooves opening axially inwardly and extending from the ra- 130

5 dially inner faces of the bonds in a generally radial direction partially through the material of the bonds to form blade retaining pockets, and a plurality of blades having end portions seated in said pockets, there being a separate pocket for each end portion of each blade and each of said end portions substantially filling out a separate pocket.

10 2. A blade ring for radial flow elastic fluid turbines comprising two axially spaced ring bonds having a plurality of separate circumferentially spaced grooves opening axially inwardly and extending from the radially inner faces of the bonds in a generally radial direction partially through the material of the bonds to form blade retaining pockets, the axially outer portions of the grooves having greater peripheral width than the axially inner portions of the grooves, and a plurality 15 of blade rings having peripherally thickened end portions seated in said pockets, there being a separate pocket for each end portion of each blade and each of said end portions substantially filling out a separate pocket.

25 3. A blade ring for radial flow elastic fluid turbines comprising two axially spaced ring bonds having a plurality of separate circumferentially spaced dovetail grooves opening axially inwardly and extending from the radially inner faces of the bonds in a generally radial direction partially through the material of the bonds to form blade retaining pockets, and a plurality of blades having peripherally dovetail end portions seated in 30 said pockets, there being a separate pocket for each end portion of each blade and each of said end portions substantially filling out a separate pocket.

35 4. A blade ring for radial flow elastic fluid turbines comprising two axially spaced ring bonds having a plurality of separate circumferentially spaced dovetail grooves opening axially inwardly and extending from the radially inner faces of the bonds in a generally radial direction partially through the material of the bonds to form blade retaining pockets, and a plurality of blades having peripherally dovetail end portions seated in 40 said pockets, said ring bonds having portions extending axially inwardly at the radially inner ends of each pocket for locking the blades in the pockets.

45 5. A blade ring for radial flow elastic fluid turbines comprising two axially spaced ring bonds having a plurality of separate circumferentially spaced grooves opening axially inwardly and extending from the radially inner faces of the bonds in a generally radial direction partially through the material of the bonds to form blade retaining pockets, and a plurality of blades having end portions seated in said pockets, there being a separate pocket for each end portion of each blade and each of said end portions substantially 50 filling out a separate pocket, the radially

inner faces of the ring bonds being grooved to form peripheral flanges adjacent to the radially inner ends of said pockets, said flanges being bent to lock the end portions of the blades in said pockets.

55 6. A blade ring for radial flow elastic fluid turbines comprising two axially spaced ring bonds having a plurality of separate circumferentially spaced grooves opening axially inwardly and extending from the radially inner faces of the bonds in a generally radial direction partially through the material of the bonds to form blade retaining pockets, and a plurality of blades having end portions seated in said pockets, there being a separate pocket for each end portion of each blade and each of said end portions substantially filling out a separate pocket, said ring bonds having portions extending axially inwardly at the radially inner ends of each 60 pocket for locking the blades in the pockets.

In testimony whereof we affix our signatures.
